Marion A. Elliotte, Detroit, Mich.

Application February 25, 1947, Serial No. 137,158

Term of patent 14 years

(Cl. D14—3)

To all whom it may concern:

Be it known that I, Marion A. Elliotte, a citizen of the United States, residing at Detroit, county of Wayne, State of Michigan, have invented a new, original, and ornamental Design for a Vacuum Leaf Loader, of which the following is a specification, reference being had to the accompanying drawings, forming part thereof.

In said drawings:

Fig. 1 is a perspective view of a vacuum leaf loader embodying my new design;

Fig. 2 is an elevational view of one side thereof;

Fig. 3 is a top plan view; and

Fig. 4 is an elevational view of the other side thereof.

I claim:

The ornamental design for a vacuum leaf loader, as shown.

MARION A. ELLIOTTE.
